Minneapolis, Minn.

Filed Nov. 13, 1961, Ser. No. 67,499

Term of patent 14 years

(Cl. D38—1)

FIG. 1

FIG. 2

FIG. 3

FIG. 4

FIG. 5

FIG. 6

FIG. 1 is a front perspective view taken from one side of an adjustable saddle stand embodying my new design shown in closed position;

FIG. 2 is a front perspective view taken from one side thereof in open position;

FIG. 3 is a top view thereof in open position;

FIG. 4 is a side elevational view thereof in closed position;

FIG. 5 is a top view thereof in closed position; and

FIG. 6 is an end elevational view thereof in closed position.

The characteristic feature of my design resides in the combination on the saddle stand disclosed of the particular saddle supporting top portion having wing-like supports hingedly connected to a stand, said supports being dis-

posed in converging or diverging relationship to each other as shown.

I claim:

The ornamental design for an adjustable saddle stand or the like, substantially as shown and described.
